United States Patent Office.

JACOB S. EVANS, OF BERKLEY, MASSACHUSETTS.

Letters Patent No. 94,483, dated September 7, 1869.

IMPROVED DUMPING-TUB.

The Schedule referred to in these Letters Patent and making part of the same.

To all whom it may concern:

Be it known that I, JACOB S. EVANS, of Berkley, Bristol county, State of Massachusetts, have invented a certain new and useful Improvement in Dumping-Pans or Tubs; and I do hereby declare the following description and accompanying drawings are sufficient to enable any person skilled in the art or science to which it most nearly appertains, to make and use my said invention or improvements, without further invention or experiment.

The nature of my invention and improvements consists in the peculiar construction and arrangement of devices described and claimed in the following specification, and shown in the drawings.

In the accompanying drawings—

A is the pan, shown in position for loading in dotted lines, and tilted for emptying in full lines. It may be made of sheet-metal or other material, and fastened into the bent strap G, which is pivoted to the bail B by the rivets M, so as to swing or vibrate freely; and the rear end of the pan is made heaviest, so that after it is tilted to empty it, it will fall back into the position shown by dotted lines ready for filling, and when filled, it should be loaded heaviest at the front end, so that it will tilt as soon as it is unlocked.

The bail B is made in the form shown, with an eye for the hook H, by which it is hoisted.

To hold the pan A in position while it is being filled and hoisted, I extend one arm of the strap G up, as shown at F, and perforate it for the end of the bolt S, which is bevelled and pressed forward by the spiral spring, shown by dotted lines in the barrel D, so that when the arm F swings up, it pushes in the bolt, which springs out into the hole in the arm, and locks

it securely. The pin I in the arm F stops it when the hole in the arm comes opposite the bolt S.

The barrel D is fastened to the bail B to contain the bolt S and its spring.

The bent rod C is fastened to the hook H, as shown in the drawings, but it may be fastened to the bail B, if preferred that way, and its lower end stepped in the tubular stand K, fastened to the arm of the bail B, as shown in the drawings.

The link T of the guy-rope or chain E surrounds this rod C, and when the pan is loaded, the link T is placed in the bend at C, and is held there by the guy until the pan is hoisted and swung to the place where it is to be emptied, when the guy is slackened and shaken to make the link T drop down on to the tail R of the bolt S, when the guy is pulled or jerked to pull back the bolt, and let the pan tilt and empty its load.

The ring J is fastened to the rod C, to hold the guy so near horizontal that it will draw the bolt when pulled for that purpose.

Having described my improvements,

I claim—

1. The combination and arrangement of the bolt S with its tail R, rod C, and link T, constructed and arranged to operate substantially as described, for the purpose set forth.

2. The unlocking or releasing the dumping-pan or tub, by means of the rope or guy used to steady the pan or tub out or in, substantially as described.

JACOB S. EVANS.
